(57) **CLAIM**

The ornamental design for a window accessory, as shown and described.

DESCRIPTION

FIG. 1 is a front, left side perspective view of a window accessory;

FIG. 2 is a front view of the window accessory as shown in FIG. 1;

FIG. 3 is a right side view of the window accessory as shown in FIG. 1;

FIG. 4 is a left side view of the window accessory as shown in FIG. 1;

FIG. 5 is a top view of the window accessory as shown in FIG. 1;

FIG. 6 is a rear view of the window accessory as shown in FIG. 1; and,

FIG. 7 is a bottom view of the window accessory as shown in FIG. 1.

The front, right side perspective view is a mirror image of the front, left side perspective view depicted in FIG. 1.

1 Claim, 6 Drawing Sheets
